UNITED STATES PATENT OFFICE.

CHARLES C. EDWARDS, OF PHOENIX, ARIZONA.

MESS AND ICE BOX.

1,221,711.

Specification of Letters Patent.

Patented Apr. 3, 1917.

Application filed August 28, 1916. Serial No. 117,199.

To all whom it may concern:

Be it known that I, CHARLES C. EDWARDS, a citizen of the United States, and a resident of Phoenix, in the county of Maricopa 5 and State of Arizona, have invented a certain new and useful Improvement in Mess and Ice Boxes, of which the following is a specification.

My invention is an improvement in mess 10 and ice boxes, and has for its object to provide a box of the character specified that when in use will provide an efficient refrigerator or cupboard and which when packed will provide a neat plain package of 15 convenient size and that will meet the requirements for army use in regard to size.

In the drawings:

Figure 1 is a perspective view of the improved box closed and ready for transportation;

Fig. 2 is a similar view with the box set up;

Fig. 3 is a section on the line 3—3 of Fig. 1;

Fig. 4 is a section on the line 4—4 of Fig. 2, both views looking in the direction of the arrows adjacent to the lines;

Fig. 5 is a partial vertical section at right angles to Fig. 4;

Fig. 6 is a perspective view of the door latch;

Fig. 7 is a perspective view of the hinge connection between the table and the box;

Fig. 8 is a similar view of one end of the 35 box, showing one of the collapsible legs;

Fig. 9 is a perspective view of the ice box and cover;

Fig. 10 is a perspective view of the door for the ice box compartment; and

Fig. 11 is a section on the line 11—11 of Fig. 4.

In the present embodiment of the invention a box or casing 1 is provided which is divided into two similar compartments by 45 a vertical partition 3. A door 5 is hinged to the open front of the box for closing the said front, and a latch mechanism is provided for holding the door closed. It will be noticed that the box is of panel construction, strips being arranged at each end, at the top and bottom and at the side wall opposite the door to frame the said walls and the door closes between the extended edges of the panel strips at the front of the end, 55 top, and bottom walls.

The door 5 is hinged to the panel strips

of one side, as indicated at 6, and legs 7 are hinged to the outer face of the door near its outer edge and ends as indicated at 8 for supporting the door in horizontal position 60 when the box is opened, and the door is held closed by the latch mechanism shown more particularly in Fig. 6, and comprising a handled latch plate 9, which is mounted to slide in a groove 10 in the outer face of the door, and retaining bars 11 are arranged transversely of the door to prevent outward movement of the latch. The handle by its engagement with the bars, limits the sliding movement of the plate. The door extends 70 the full length and width of the box. The legs 7 have angular lugs at their free ends forming feet, as shown in Fig. 4, and the outer face of the door is notched or recessed for receiving these feet when the legs are in 75 folded position.

Another door 12 is provided in the top of the ice compartment, the said door being cut in the top of the box and fitting flush with the top when closed. Dowel pins 13 80 are provided at the inner end of the door, the said pins engaging openings in the adjacent end of the cut away top and a spring latch 14 is provided on the inner face of the door for holding the door closed, the said latch engaging a pin on the adjacent end wall. The panel strips at the side of the top are cut away for a greater distance than the length of the door to form extensions 4 at the inner end of the door which engage 90 above the top to firmly hold the door in place.

In removing the door the latch must be disengaged from the inside of the box, that is, the door 5 must be opened before access 95 may be had to the latch of the door 12. In closing the door 12 the dowel pins are engaged and the other end of the door is dropped into place, the latch automatically locking the door. A metal pan or receptacle 100 15 for ice is provided, and this receptacle is adapted to be seated on inwardly extending flanges 15^a at the opening for the door 12, as clearly shown in Figs. 4 and 5. A cover 16 of wood or the like is provided for inclosing the pan and the ice therein. This cover is of a size to fit within the paneling at the top and the outer end has an extension 16^a adapted to extend through the door opening for the door 12 to prevent longitudinal movement of the cover. It will be 110 noticed that the compartment having the

door 12 is suitably lined with metal, for instance, and a layer of non-heat conducting material is arranged between the metal lining and the walls of the compartment, the said layer being of any suitable or desirable material.

The box is provided with a leg at each corner, and the legs are mounted to slide on the box into and out of operative position. 10 Each of the legs 17 (see Fig. 8), is shown as slideable in guide hasps 18 on the adjacent wall, and each leg is provided with an angular spring latch 19 intermediate its ends for engaging the paneling at the bottom of the 15 box to limit the extending movement of the leg. A similar but heavier latch 20 is arranged above each leg on the adjacent wall and in position such that when the latch 19 engages the paneling at the bottom of the 20 wall, the upper end of the leg will free the latch 20 so that it may spring out to prevent collapse or inward sliding movement of the leg. It will be noted from an inspection of Fig. 2 that these legs 17 are arranged on 25 the rear wall at the ends thereof, and on the end walls near the front, so that they do not interfere with the movement of the door 5.

A table 21 in the form of a plate is provided for coöperation with the box, and the 30 said table is arranged to be placed in the position of Figs. 1 and 3, that is, on the outer face of the door 5 and connected to the box; or in the position of Fig. 2, that is, in the plane of the top of the box and also connected therewith. The said plate 21 is provided at one side edge with hinge leaves 22 each of which has a pintle 23 in connection therewith. These pintles are adapted to engage hinge leaves 24 on the box near the hinge 35 connection of the door 5, or hinge leaves 25 at the top of the rear wall of the box. By engaging the pintles with the hinge leaves 24, 25 and moving the table longitudinally in its plane, it will be evident that 40 the pintles may be engaged with the said hinge leaves and by moving the table in the opposite direction it may be quickly and easily detached from the leaves. This table is reinforced on one face with reinforcing 45 strips 26, these strips being on the outer face when the table is in the position of Fig. 1, and on the under face when the table is in the position of Fig. 2.

The table is also provided with a pair of 50 extensible and contractible legs which also act as clamping members for connecting the table to the box door 5. Each of these legs consists of a section 27 hinged to the table and a section 28 mounted to slide in the section 27. The section 27 has its side edges turned over upon the body to form guides for engagement by the section 28, and the section 28 has a headed pin 29 engaging a longitudinally extending slot 30 in the section 27.

Openings are also provided in the two sections which are adapted to register when the sections are in retracted or extended position. These openings are adapted to be engaged by a locking ring 31 to hold the 70 parts in either position. The outer end of each section 28 has a laterally extending lug which is adapted to engage the opposite side of the box when the table is in the position of Figs. 1 and 3. These lugs are of 75 such length that when the table is in the position of Fig. 4, they will support the same in horizontal position, while when the table is in the position of Figs. 1 and 3, and the legs are contracted, the laterally extending lugs 32 will engage the opposite side of the box to clamp the table to the box. Pins 33 are provided at the said opposite side of the box for engagement by openings in the lugs, it being understood that the locking 80 rings lock the legs in position at this time. 85

During transportation the parts occupy the position of Fig. 1, the ice pan and the cover being placed in the refrigerating compartment with the door 12 closed and with 90 the table 21 locked in position over the door 5. The other compartment of the box serves for storage, and when it is desired to use the box the parts are arranged as shown in Figs. 4 and 5, the door 5, however, being 95 closed except when access is desired to the interior of the box. The articles to be refrigerated are placed in the refrigerating compartment below the ice pan and other articles may be placed in the other compartments. 100

I claim:—

1. A device of the character specified, comprising a box having a transverse partition dividing the box into a storage compartment and a refrigerating compartment, the front of the said box being open and a door hinged to the box at the front and closing the front, legs slidably connected with the rear wall and the end walls of the box for supporting the box in elevated position, means in connection with the legs and box for holding the legs extended, means for limiting the extending movement of each leg, a leg hinged to the door and holding the door in horizontal position when the door is open, a table adapted to fit over the front wall of the box or to extend in the plane of the top from the rear wall, and having means for detachably engaging the box at either point, said table having at its outer edge extensible and contractible members forming legs when the table is in extended position, and forming clamps for securing the table to the box when said 110 table is superposed on the door. 115

2. A device of the character specified comprising a box having a transverse partition dividing the box into a storage compartment and a refrigerating compartment, the front 120

130

of the said box being open and a door hinged to the box at the front and closing the front, a table corresponding in size to the front of the box, and means in connection with the 5 table and the box for hinging the table adjacent to the hinged connection of the door or at the upper side of the rear wall of the box, said table having extensible legs for supporting it in horizontal position.

10 3. A device of the character specified comprising a box having a transverse partition dividing the box into a storage compartment and a refrigerating compartment, the front of the said box being open and a door hinged to the box at the front and closing the front, the box having an opening in its 15 top at the ice compartment, a door for closing the opening, means in connection with the door and the box and inaccessible from the exterior of the box, for holding the door closed.

15 4. A device of the character specified comprising a box having a door opening in its top and a door for closing the opening, means inaccessible from the exterior of the box for holding the door closed, an ice pan adapted to seat within the opening and to 20 provide a space between the opening and the pan, the box having means for supporting the pan in the opening, and a cover of non-heat conducting material fitting over the ice pan and closing said door opening, said pan and cover being of a size to fit within the box.

25 4. A device of the character specified com-

prising a box having a transverse partition dividing the box into a storage compartment and a refrigerating compartment, the front of the said box being open and a door hinged to the box at the front and closing the front, the box having an opening in its top at the ice compartment, a door for closing the opening, and means in connection with the door and the box and inaccessible from the exterior of the box, for holding the door closed. 30

5. A device of the character specified comprising a box having a door opening in its top and a door for closing the opening, means inaccessible from the exterior of the box for holding the door closed, an ice pan adapted to seat within the opening and to 35 provide a space between the opening and the pan, the box having means for supporting the pan in such position, and a cover for the opening, seated on the box about the opening, said pan and cover being seated within the box when the door is closed. 40
